INVENTOR

UNITED STATES PATENT OFFICE.

OSCAR OLSEN LEE, OF CHICAGO, ILLINOIS.

TELEPHONE SIGNALING MECHANISM.

SPECIFICATION forming part of Letters Patent No. 752,909, dated February 23, 1904.

Application filed January 11, 1900. Serial No. 1,064. (No model.)

To all whom it may concern:

Be it known that I, OSCAR OLSEN LEE, a citizen of the United States, residing at Chicago, in the county of Cook and State of Illinois, have invented a new and useful Telephone Signaling Mechanism, of which the following is a specification.

This invention relates to telephone signaling mechanism.

15 The object of the invention is to provide a construction and arrangement of switching mechanism in connection with telephone signaling apparatus whereby the signal may be effected automatically and without the use of a generator.

A further object of the invention is to provide an arrangement of telephone signaling apparatus wherein a portion only of the same battery employed for energizing the signal-20 circuit is used in the talking-circuit.

25 Other objects of the invention will appear more fully hereinafter.

The invention consists, substantially, in the construction, combination, location, and arrangement of parts, all as will be more fully hereinafter set forth, as shown in the accompanying drawings, and finally pointed out in the appended claims.

30 Referring to the accompanying drawings, and to the various views and reference-signs appearing thereon, Figure 1 is a diagram showing the electrical circuits and relative arrangements of the various parts of the apparatus at a subscriber's station. Fig. 2 is a broken view 35 in detail, somewhat diagrammatic, showing the position of the receiver-hook during the completion of the signaling-circuit. Fig. 3 is a view similar to Fig. 2, showing the arrangement of circuits after the signaling-circuit has 40 been broken and with the talking-circuit completed.

The same part is designated by the same reference-sign wherever it occurs throughout the several views.

45 Referring to the accompanying drawings, A designates a lever, suitably pivoted; as at B, and carrying a hook C, adapted to receive and support the receiver D. A spring Y is ar-

ranged to exert its tension upon lever A in a direction to rock said lever about its pivot B, 50 the tension of said spring being overcome by the weight of the receiver when imposed upon the hook C of said lever.

E designates an extension of lever A beyond its point of pivotal support. 55

F, F', and G designate contact-springs with which the extension E co-operates.

S^B designates a signal-bell.

O O designate battery-cells.

M designates an induction-coil; T, the soft-iron core of said coil; N, a vibrator or rheotome; N', the contact-screw of said rheotome or circuit-breaker, and Q a transmitter. 60

Suitably mounted upon but insulated at I from lever A is an arm H, arranged to project 65 between contact-springs J J', suitably insulated from each other and secured by screws K K'. The contact-springs J J' are spaced apart, so as to provide sufficient room therebetween to receive the arm H without contact with either 70 of said springs when lever A is in its lowermost or depressed position; but when said lever is rocked toward raised position—as, for instance, when the receiver is removed from hook C—the arm H makes contact with both 75 springs J J' in passing, and when the lever A is in its extreme uppermost position the arm H passes beyond the ends of said springs J J' to again break electrical connection therebetween, reference-sign L designating the point 80 at which simultaneous contact is made with both springs J J' by arm H.

Having now described or referred to the various parts, I will now explain the electrical connections thereof. First, when the receiver 85 is upon its hook and lever A is in its lowermost position circuit is broken between the contact-springs J J' and a circuit completed between contact-spring G and an arm E' of the extension of lever A, as clearly shown in 90 Fig. 1. This is the position of the parts when the apparatus is not in use. Thereupon the following circuit is completed: from point R', which represents the circuit-terminal of one of the line-wires, thence through wire V, bell S^B, 95 wire V, contact-spring G, extension E' of lever

A, to the pivot B of said lever, through wire P², wire P³ to point R, which indicates the terminal of the other line-wire. Thus the signal-circuit is completed, showing the apparatus in condition ready to receive a signal from the central or a distant subscriber's station. Now suppose the subscriber desires to call up the central station or another distant subscriber. The first operation is to raise the receiver from its hook C, whereupon under the influence of spring Y lever A is rocked about its pivot B toward its extreme upper position. The first action which takes place is the breaking of circuit between contact-spring G and the arm E' of the extension of lever A, thereupon breaking the signal or bell circuit above traced. As the rocking movement of lever A continues the arm H thereon, operating between the contact-springs J J', arrives at the point L and makes simultaneous contact between said springs, thereby bridging the same, thereupon completing the local-battery circuit as follows: from one terminal W² of the battery O O, through wire P', the circuit-breaker N, wire P', to contact J', arm H, contact-spring J, wire P'', the primary winding of induction-coil M, to wire P⁴, to the terminal W' of battery O O. At the moment of completion of the above circuit by the bridging of the space between contact-springs J J' the extension E'' of lever A makes contact with spring F, thereupon completing the following circuit: from binding-post R', wire S, receiver D, wire S, secondary winding of induction-coil M, wire S, contact-spring F, extension E'' of lever A, pivot B of said lever, wire P², wire P³, to binding-post R and to the other line-wire. The making of the local-battery circuit through the bridging of the space between the contact-springs J J' operates the rheotome or vibrating circuit-breaker N at a high rate of speed, thereby inducing electrical pulsations in the secondary circuit of the induction-coil. The windings of said secondary coil being at the same instant included in the line-circuit, a signal-current is sent to line and which current utilizes in the production thereof the full strength of all the cells of the local battery, thereby insuring a positive and efficient actuation of the signal device—such, for instance, as a drop at the switchboard, or a polarized bell, or a harmonic signal from the receiver of another telephone, or other suitable signal device at the said distant station or the central station. The continued rocking movement of lever A toward its extreme upper position carries arm H free or clear of contact with springs J J', thereby breaking the signal-circuit above referred to and which includes the contact-springs J J'. Such parallel movement, however, of lever A does not break the circuit between contact-spring F and the extension E of the receiver-lever. Therefore

the circuit of the secondary of induction-coil M as above traced remains completed. However, when lever A reaches its extreme upper limit of movement the extension E of said lever makes contact with spring F', thereupon completing the following circuit: from the terminal W of a portion only of the battery— as, for instance, from only one of the elements or cells of such battery—through wire P, spring F, arm E of the extension of lever A, wire P², transmitter Q, wire P to primary winding of induction-coil M and wire P⁴ and the other terminal W' of the same portion or cell of battery O O. This constitutes the talking-circuit, and hence it will be seen that I utilize in the talking-circuit a portion only of the same battery-power employed in the signaling-circuit.

When a signal is sent—that is, when the signaling-circuit is completed by the raising of the receiver from its supporting-lever A—it is obvious that said lever A may be held in position to close the circuit between springs J J' as long as desired to prolong the signal, thereby giving the vibrator sufficient time to interrupt the current, and when the signal has been given and the receiver-weight entirely relieved from its supporting-lever the apparatus is placed in condition for talking and with only a portion of the battery-power in circuit.

Having now set forth the object and nature of my invention and a construction and arrangement of parts embodying the principles thereof, and having set forth and described the purpose, function, and mode of operation thereof, what I claim as new and useful and of my own invention, and desire to secure by Letters Patent of the United States, is—

1. A telephone signaling apparatus, comprising a local battery, an induction-coil, a rheotome or vibrator therefor, a receiver-support and an electric signaling apparatus, a circuit from said battery leading through the primary of the induction-coil and through the rheotome thereof, said circuit being made by the movement of the receiver-lever, and additional circuits controlled by said receiver-support, normally throwing said signaling apparatus into circuit with the line-wires, and arranged to throw the secondary of the induction-coil into circuit with said line-wires and a portion of the said battery together with the transmitter, into circuit with said primary coil, at the limit of upward movement of the receiver-support, as and for the purpose set forth.

2. A telephone signaling apparatus, comprising a local battery, an induction-coil, a rheotome or vibrator therefor, a receiver-support and an electric signaling apparatus, a circuit from said battery leading through the primary of the induction-coil, and through

the rheotome thereof, said circuit being made by the movement of the receiver-lever, contacts on the receiver-support, and a series of coöperating springs connected respectively to 5 the secondary of the induction-coil, the signal apparatus, and an intermediate point in the electric battery, whereby the signaling apparatus is normally in circuit with the line-

wires, but said battery and induction-coil are thrown into a talking-circuit upon movement 10 of said receiver-support to its limit of upward movement, as and for the purpose set forth.
